G. W. DREW,
FRUIT SLICING MACHINE,
APPLICATION FILED OCT. 4, 1911.

1,244,038.

Patented Oct. 23, 1917.

UNITED STATES PATENT OFFICE.

GEORGE W. DREW, OF OAKLAND, CALIFORNIA.

FRUIT-SLICING MACHINE.

1,244,038.

Specification of Letters Patent. Patented Oct. 23, 1917.

Application filed October 4, 1911. Serial No. 652,841.

To all whom it may concern:

Be it known that I, GEORGE W. DREW, a citizen of the United States, residing at Oakland, in the county of Alameda and 5 State of California, have invented certain new and useful Improvements in Fruit-Slicing Machines, of which the following is a specification.

This invention relates to improvements in 10 fruit slicing machines, the object of the invention being to provide a fruit slicing machine which can be made at less cost, be more durable, less complicated, made positive in action, less liable to get out of order, 15 more easily understood and operated than those heretofore used.

In the accompanying drawing, Figure 1 is a front view of the machine. Fig. 2 is a side view of the machine. Fig. 3 is a detail 20 of the inner end of a hanger, cross section of knife, longitudinal section of a hollow shaft and cross section of a collar. Fig. 4 is a cross section of the hollow shaft shown in Fig. 3. Fig. 5 is a longitudinal view of 25 a knuckle joint. Fig. 6 is a modified form of the hollow shaft shown in Fig. 3, and also modified form of Fig. 5. Fig. 7 is a modified form of the hollow shaft shown in Fig. 3. Fig. 8 is a modified form of Fig. 5. 30 Fig. 9 is a partial face view of the hanger 3, sectional view of the lower end of the same, sectional view of the shaft 7, collar 14, cutter 6 and knuckle joint 8.

Referring to the drawing, 1 indicates a 35 semicircular cast iron frame or support with a slot 2 through which bolts 25 are placed to hold the hanger 3 in proper position; upon the support are assembled the hangers 3 which carry the slicing knives 6. These 40 hangers converge toward the axis of the frame. Each end of this frame has a base or foot 29 extending forward and back for securing it to a stand. On the bottom of one of these bases is attached a box 11 to 45 carry the shaft 10. Upon the side of this box is attached the hanger 19, Fig. 2, to carry the shaft 26.

The hangers 3 are provided with slots 4 through which the bolts 25 are placed. 50 These slots permit the hanger to be advanced as the diameter of the knives through use is diminished. The end of the hanger 3, toward the axis of the frame is provided with an opening 20, Fig. 9, through which 55 the hollow shaft 7 is placed, the opening forming a box for the shaft 7. 24 is an ad-

justing screw in the outer end of the hanger 3, and rests upon the outer edge of the frame 1.

The shaft 7 is provided with a flange 18 60 Fig. 9 which is turned inward to bring the cutter 6 near the center of bearing. To this flange the cutter 6 is secured by means of screws or bolts. This shaft also has a square hole 16 running through it longitudinally. 65 About midway between the ends of this square opening are lugs 17, running across the sides of the opening to prevent the knuckle joint from passing or dropping through the opening and holding it in 70 proper position. This shaft is round outside and is provided with a thread at one end to engage the collar 14, Fig. 3. Between this collar 14 and the collar 18 is placed the hanger 3. 6 is a circular knife 75 having a sharp edge and is firmly secured to the shaft 7 by means of screws or bolts, 15, Fig. 3. These knives are so placed upon the frame 1, that their lower edge converge to a common point at the center of the con- 80 veyer belt 13. 8 is a knuckle joint in proper working position. 9 is a square opening in the upper end of the shaft 10 and fits the end of the knuckle joint Fig. 5; into this opening is placed one end of the first knuckle joint 8. 85 The other end of this knuckle is placed in the adjacent end of the square hole of the first shaft 7, the second knuckle having one end placed in the other end of the first shaft 7 and engaging the second shaft 7. In this 90 manner all the shafts 7 are connected up by knuckle joints 8. Thus it will be seen that when the shaft 10 revolves, the shafts 7 and their respective knives also revolve.

10 is a perpendicular shaft with its upper end adapted to the style of knuckle joint used to connect it with the first of the series of shafts 7. It may be a bronze or iron casting or plain shaft with the proper fitting secured to the upper end. 12, Figs. 1 and 95 2, are bevel gears and connect the rod 26 with the shaft 10. 12' Fig. 2 are bevel gears and connect the rod 26 with the main drive shaft 27; by this connecting rod 26 the main drive shaft 27 is connected with the shaft 100 10 (a belt drive may be used in place of this rod and gear drive). The drive pulley 28 for the conveyer belt 13 is placed on the main drive shaft. By revolving the main shaft 27 the entire machine is set in motion. 105 13, Fig. 1 is an end view of the conveyer 13, shown in Fig. 2. The top of this con-

veyer runs in the same direction as the bottom of the knives 6. It is used for carrying the fruit to and through the knives and depositing it in receptacles at the back of the machine.

Fig. 5 is a knuckle joint of the form preferred for my use. The ends and body part are square in cross section; the body portion is smaller than the ends to admit of an oscillating movement without striking and binding on the sides of the opening in the shaft 7. The ends are made of a size to fit the opening in the shaft 7. The four edges 23, Fig. 5, of each end are rounded to a diameter equal to the width of the square opening in the shaft 7. This will allow the knuckle to oscillate without binding. The knuckle is made of a proper length to allow for adjustment as the diameter of the knives 6, is diminished through use and the hangers 3, are advanced bringing the ends of the shafts 7 closer together. The knuckles are made of metal, either bronze, cast iron or forged steel.

Fig. 6 is a modification of 7 and Fig. 5, showing a modified form of the shaft 7 with a square opening through it longitudinally. This opening is larger in the center than at the ends to permit the ends of this form of knuckle to oscillate. The inside edges 30 of the ends are rounded similar to the edges of the ends of Fig. 5.

Fig. 7 is also a modification of 7 having a round hole through its center longitudinally instead of the square hole in the former. Through each end of this shaft and the center of the hole are placed pins 21. Upon these pins the knuckle Fig. 8, works; the slots 22 fitting the pins 21.

Fig. 8 is a modified form of Fig. 5 being round in cross section to fit the opening in Fig. 7.

I claim,

1. In a slicing machine, the combination of a frame, a slotted semicircular supporting beam, the ends resting upon said frame, a series of hangers assembled upon said supporting beam in semi-circular order and on radial lines, a series of rotatable tubular shaft cutter mountings journaled in the

convergent lower ends of said hangers, a knuckle joint member adapted to enter the opposite ends of the bore of said tubular shaft cutter mountings, and a power transmission connection to one of the knuckle joint members to rotate all of the knuckle joint members and tubular shaft cutter mountings.

2. In a slicing machine, the tubular shaft cutter mounting 7, having collar parts 14 and 18 for the purposes described and body part longitudinally bored or recessed to receive a knuckle joint member.

3. In a slicing machine, a rotatable tubular shaft cutter mounting provided with a central longitudinal bore polyhedral in cross section and having an integral cutter carrier flange on one of its ends, an engaging removable flange on its other end and journal space between said flanges.

4. In a slicing machine, a rotatable recessed shaft cutter mounting provided with central longitudinal recesses polyhedral in cross section and having an integral cutter carrier flange on one of its ends, an engaging removable flange on its other end, and journal space between said flanges.

5. In a slicing machine, the combination of a hanger 3, with its journal end offset to one side, a rotatable tubular shaft cutter mounting journaled in said hanger, having an integral cutter carrier flange 18 turned in and a knuckle joint member co-operating with said shaft cutter mounting.

6. In a slicing machine a rotatable tubular or recessed shaft cutter mounting with an integral cutter carrier flange turned in.

7. In a slicing machine the combination of a hanger 3 with its journal end offset to one side, a rotatable shaft cutter mounting journaled in said hanger, having an integral cutter carrier flange 10 turned in.

In witness whereof, I have hereunto set my hand in the presence of two subscribing witnesses.

GEORGE W. DREW.

Witnesses:

E. P. VAUGHAN,
IRA VAUGHN.
